UNITED STATES PATENT OFFICE.

HORACE M. SPRAGUE, OF DENVER, COLORADO.

QUICK-ADJUSTMENT WRENCH.

1,394,369.

Specification of Letters Patent. Patented Oct. 18, 1921.

Application filed December 27, 1920, Serial No. 433,389.

To all whom it may concern:

Be it known that I, HORACE M. SPRAGUE, a citizen of the United States of America, residing in the city and county of Denver 5 and State of Colorado, have invented new and useful Quick-Adjustment Wrenches, of which the following is a specification.

This invention relates to improvements in quick adjustment wrenches of the class 10 known as monkey wrenches.

The object of the invention is to provide a wrench of this character having the usual fixed and slidable jaws, the slidable jaw having a threaded adjustment nut which is 15 adapted to engage the threaded shank of the wrench in the usual manner, but which is pivotally connected to the said movable jaw so that it may be swung back out of engagement with the teeth on the shank, thus permitting the slidable jaw to be quickly moved 20 up or down on the shank; the nut, when moved again into engagement with the teeth of the shank, serving to adjust the jaw in the usual manner, and to hold the same at 25 the desired point of adjustment.

Further, to provide a wrench in which the slidable jaw is provided with an adjustment nut in sliding engagement with a stem which is in swinging engagement with the jaw, said 30 nut being under a spring tension which prevents accidental disengagement of the nut from the teeth of the shank.

These objects are accomplished by the mechanism illustrated in the accompanying 35 drawings, in which:

Figure 1 is a side elevation of a wrench constructed in accordance with my invention.

Fig. 2 is a view similar to Fig. 1, the slidable jaw, and swinging adjustment nut 40 being shown in section, and

Fig. 3 is a transverse sectional view on the line 3—3 of Fig. 1.

Referring to the accompanying drawings:

The numeral 1 designates the shank portion of the improved wrench, 2 the handle, and 3 the fixed jaw, and these parts are preferably formed of a single piece of metal, though the usual wood hand grips may be screwed upon the handle if desired. The 45 shank is of slightly less thickness than the width of the jaw, and upon the shank is mounted the slidable jaw which is made up of a metal block 4, constituting the jaw proper, and a U-shaped guide 5, which surrounds three sides of the shank, and is slidably mounted thereon, and is secured to the 50 jaw 4, by pins 6 and 7. The sides of the guide overlap a portion 8, of the jaw 4, which is reduced to the thickness of the shank, and beyond the edges of the guide the jaw widens 60 out to the full width of the fixed jaw 3, or of the guide, which is also the same width as the jaw 3, as is clearly shown in Fig. 3.

The edge of the shank adjoining the jaw 4, is threaded or provided with teeth 9, and 65 these threads or teeth are flat on their upper faces, and inclined on their under faces, the incline being downward from their outer edges, as shown. The reduced or narrow portion 8, of the jaw 4, is formed with a 70 recess 10, which is cut in from the inner edge of the jaw and extends from its lower end to a point slightly beyond, where the pin 7, passes through the jaw, and the upper half of a stem 11, lies in the recess 10, and 75 is pivotally mounted on the pin 7, which passes through a hole in the upper end of the said stem. The lower end of this stem is provided with a head 12, and before securing the stem upon the pin 7, an adjust- 80 ment nut 13, having an axial hole 14, is slipped upon the stem. The lower half of the hole 14, is counterbored to form a chamber 15, of the diameter of the head 12, on the lower end of the stem, and an expansion 85 coil spring 16, surrounds the stem, and bears at one end against the head of the stem, and at its other end, against a shoulder 17, formed at the junction of the hole 14, and the counterbore 15, the spring 16, serving to hold the 90 upper end of the nut 13, tightly against the lower end of the jaw 4, and thus prevent accidental outward swinging of the stem 11, with the nut 13. The nut 13, is cylindrical 95 in form, and of slightly less diameter than the widest part of the jaw 4, and a thread 18, is formed on the periphery of this nut, which is adapted to mesh with the threads 9, on the shank of the wrench. The under face of the thread 18, however, is flat, while its upper face inclines upward from the outer edge of the thread, and by this arrangement, the under or flat face of the thread on the nut engages the upper or flat faces of the threads or teeth on the shank, while the inclined upper face of the thread on the nut engages the inclined under face of the shank threads. Thus yielding or slipping of the jaw 4, under downward thrust, is impossible, owing to the engagement of the flat face of the thread 110 on the nut, with the corresponding flat faces of the threads on the shank; but when the

jaw 4, is pushed toward the jaw 3, the contact of the inclined faces of the threads on the nut and shank will cause the stem 11, with the nut, to swing outward, thus throwing the nut out of engagement with the teeth of the shank, and thereby permitting the jaw 4, to be slipped upon the shank, without manually swinging the nut out of operative position.

10 The lower end of the jaw 4, is inclined downwardly from the recess 10, as shown at 19, to form a slight cam surface, which is engaged by the upper end of the nut 13, when the same is swung outward to dis-
15 engage it from the shank threads, and this engagement of the upper end of the nut with the said cam surface causes a downward sliding of the nut on the stem 11, whereby the spring 16, is contracted, and causes the
20 nut to bear with greater force against the jaw, so that when the outward swinging pressure on the nut is released, the spring 16, will cause the nut to swing back into engagement with the shank threads, and hold it
25 there against accidental disengagement. As the diameter of the nut is slightly less than the thickness of the jaws, the nut cannot come in contact with any surface over which the wrench is moved when in operation, and
30 thus accidental turning of the nut is prevented.

The ends of the pins 6 and 7, are spread or riveted, so as to hold the pins in place.

In operation, when it is desired to slip 35 the jaw 4, down from a closed position or from a slightly open position to a wider open position, the nut is swung to one side, as shown in Fig. 2, so as to disengage its thread from those of the shank, and the jaw
40 is then slipped to, or approximately to the desired position, and the nut is swung again into mesh with the shank threads. The wrench is then applied to the object, such as a nut or bolt head, which is to be turned, or
45 held stationary, as the case may be, and if any finer adjustment of the jaw is required, either to increase or diminish the space between the two jaws, such adjustment is made by turning the nut, as in wrenches of the
50 ordinary construction. The sliding jaw can be instantaneously slid from a wide open to a closed position, or any intermediate position, by pushing upward on the said jaw, which causes the inclined faces of the nut
55 thread to slip over the corresponding faces of the shank threads, as previously described.

Having described my invention, what I claim as new and desire to secure by Letters
60 Patent, is:

1. In a wrench of the character described, a toothed shank having a fixed jaw thereon, a jaw slidably mounted on said shank, a stem in swinging engagement with said jaw
65 having an abutment head on its free end, a

threaded nut slidably mounted on said stem having a counterbore, which incloses said abutment head, an expansion coil spring on said stem interposed between said abutment head and the end of said counterbore, to hold said nut against the bottom of said jaw, said nut being normally in threaded engagement with said shank, thereby to adjust said jaw on said shank and to permit the quick sliding adjustment of said jaw on said shank, when out of mesh with said shank, and means for causing said nut to swing back into mesh with said shank, and for holding said nut in such position.

2. In a wrench, a toothed shank having a fixed jaw, a jaw slidably mounted on the shank, a stem in swinging engagement with said jaw having an abutment head on its free end, a threaded nut slidably mounted on said stem and having a flat upper end for engaging the lower end of said jaw, and having a counterbore which at all times incloses the abutment head of said stem; an expansion coil spring on said stem interposed between said abutment head and the end of said counterbore, to hold said nut against the lower end of said jaw, said nut being normally in threaded engagement with said shank, thereby to adjust said jaw on said shank, and to permit the quick sliding adjustment of said jaw on said shank when out of mesh with said shank, and an inclined face on the lower end of said jaw upon which the upper end of said nut slides when the nut is swung out of mesh with the shank, said inclined face and the expansion force of said spring causing said nut, when released, to swing back into mesh with said shank, and to maintain such position.

3. In a wrench, a toothed shank having a fixed jaw, a slidable jaw on said shank, a stem pivoted at one end to said jaw and having a head on its free end, a threaded nut slidably mounted on the stem and normally in mesh with said toothed shank, said nut having a counterbore which houses the head of said stem, said head fitting snugly but slidably in said counterbore; an expansion coil spring surrounding said stem and interposed between said head and the end of said counterbore, said jaw having an inclined face on its lower end which is engaged by said nut when the same is swung out of mesh with the shank, thereby sliding said nut on the stem and compressing said spring, the expansion force of said spring in conjunction with the inclined face causing the nut, when released, to swing back into mesh with the shank.

In testimony whereof I affix my signature in presence of two witnesses.

HORACE M. SPRAGUE.
